[57] CLAIM

The ornamental design for a food chopper, as shown and described.

DESCRIPTION

FIG. 1 illustrates a top, front and side perspective view of our new design for a food chopper;

FIG. 2 illustrates a top plan view thereof;

FIG. 3 illustrates a right side elevational view thereof;

FIG. 4 illustrates a front elevational view thereof;

FIG. 5 illustrates a rear elevational view thereof; and,

FIG. 6 illustrates a bottom plan view thereof.

The broken line showing a processor blade in FIGS. 1-5 is environmental only and forms no part of the claimed design.

FIG. 2

FIG. 3

FIG. 5

FIG. 4

FIG. 6
